UNITED STATES PATENT OFFICE.

BURNETT Y. TIFFANY, OF NEW YORK, N. Y., ASSIGNOR TO THE TIFFANY & COMPANY, OF SAME PLACE.

DESIGN FOR A SPOON OR SIMILAR ARTICLE.

SPECIFICATION forming part of Design No. 31,345, dated August 8, 1899.

Application filed July 17, 1899. Serial No. 724,147. Term of patent 7 years.

To all whom it may concern:

Be it known that I, BURNETT Y. TIFFANY, a citizen of the United States, and a resident of the city, county, and State of New York, have invented a new and original Design for Spoons, Forks, or Similar Articles, of which the following is a specification.

This invention relates to a design to be applied to spoons, forks, and similar articles; and it consists of the novel ornamentation set forth in the accompanying drawing and description.

By reference to the drawing, which shows a spoon bearing the design upon its surface, it will be seen that the design is an arrange-

ment and grouping of leaf forms, some of the outlines of which form a portion of the configuration of the spoon, fork, or other article.

What I claim as new, and desire to secure by Letters Patent, is—

The design for a spoon, fork or similar article, substantially as shown and described.

In testimony whereof I have signed my name to this specification in the presence of two subscribing witnesses.

BURNETT Y. TIFFANY.

Witnesses:

F. R. MAGEE,
JOHN W. CLEARMAN.
